UNITED STATES PATENT OFFICE.

WILLIAM CARTER, OF GLASGOW, SCOTLAND.

MECHANISM FOR PASTING BOTTOMS OF PAPER BAGS.

SPECIFICATION forming part of Letters Patent No. 611,055, dated September 20, 1898.

Application filed December 28, 1897. Serial No. 663,818. (No model.) Patented in England May 12, 1897, No. 11,784.

To all whom it may concern:

Be it known that I, WILLIAM CARTER, lithographic printer, a subject of the Queen of Great Britain, and a resident of the city of Glasgow, Scotland, have invented certain new and useful Improvements in and Connected with Mechanism for Pasting the Bottoms of Paper Bags, (patented in Great Britain, No. 11,784, May 12, 1897,) of which the following is a specification.

This invention relates to a simple device for pasting down the folded parts at the bottoms of paper bags.

In carrying out the invention I construct a table of any suitable material and fit thereon an oblong or other desired form of paste vessel having a movable front gate. Working in guides along the bottom of this vessel is a tongue or blade, which when necessary can be shot forward out in front of the paste vessel and then drawn back again within it by means of lever mechanism connected to a cross-shaft underneath the table, which latter is acted upon by treadle or other mechanism and by a spring or such like. The arrangement is such that when it is desired to paste down the triangular-shaped folded-over parts at the bottom of the bag the tongue, with paste on its upper side, is shot forward under the action of the treadle or the like over the bottom part of the bag, and the triangular parts can then be easily folded over on top of the tongue, so as to take the paste therefrom, whereupon the tongue is withdrawn by relieving the treadle and the triangular parts merely pressed tightly down on the bottom of the bag by the fingers. By raising or lowering the gate of the paste vessel the amount or thickness of paste on the tongue can be regulated.

As it is necessary in the case of glazed or thick paper bags to keep them pressed for some time in order to make the paste adhere firmly, I provide at the front or other part of the table a pressing-board, consisting of a strip of wood or metal, which is held tightly against the under side of the table by means of rubber or other springs or equivalent. This board has a guideway in it. The table is also recessed or cut out to enable the newly-pasted bags to be inserted in the guideway

and between the board and the table, so as to be subjected to pressure. The newly-pasted bags are placed in the guideway one after the other until they gradually fill it, when they one by one, as fresh bags are inserted, tumble over at the end of the guide into a receptacle.

In order that my said invention may be properly understood, I have hereunto appended three explanatory sheets of drawings, whereon—

Figure 1 is an end view of the apparatus. Fig. 2 is a plan. Fig. 3 is a detail view. Fig. 4 is a part section on the line xx , Fig. 2. Fig. 4^a is a detail view. Fig. 5 is a plan view, and Fig. 6 an end view, of the paste vessel. Fig. 7 is a perspective view of a satchel-bag flattened out and before turning in and pasting the side flaps, and Fig. 8 is a side view of the bag after the flaps are turned in and pasted.

Referring to the drawings, whereon the same reference-letters wherever repeated indicate the same parts, a is the table of the machine, and, as shown, it is supported upon suitable standards $b b'$.

c is the paste vessel, which is secured removably by screws c' to a plate d , let into the table a . (See particularly Figs. 5 and 6.)

c^2 are flanges at the bottom of the paste vessel. The paste vessel is made with vertical guides $c^3 c^4$, in which is movably fitted a front gate c^5 . This gate can be adjusted to any desired position in the guides $c^3 c^4$, so as to regulate the outflow of the paste, and when adjusted can be clamped in position by the screw c^6 .

e is the movable tongue or blade, which, as shown, may be of triangular shape. In other words, the upper side of the tongue inclines in two directions, like a roof. This tongue can slide back and forward along the bottom of the paste vessel. In Fig. 5 the full lines show the tongue in its back position, while the dotted lines e' indicate its out or forward position.

The mechanism for actuating the tongue e consists of a double bell-crank lever f , which is fulcrumed at f' to a downwardly-projecting arm g , attached to the under side of the plate d . The upper ends of the double bell-crank lever f are forked, as shown at f^2 .

Attached to the short arm of the lever *f* is a wire or band *h*, which extends downward to a treadle *i*.

j is a spring which brings back the lever *f* after each depression of the treadle *i*.

K is an opening cut in the table *a*.

The tongue *e* is connected to the bell-crank *f* by means of a swiveling double-armed link *e'*. *e²* are the arms of the link.

10 *d²* is a stop on the plate *d*.

The mechanism for pressing the paper bags after being pasted consists of the board *l*, which is provided with a guide-plate *l'* at one side. As shown clearly at Figs. 1, 2, and 3, *15* the guide *l'* is hinged to the table at *l²*, and the board *l* is pressed upward against the bottom of the table by means of a spiral spring *m*. This spring at its upper end is fitted in a recess in the bottom of the board *l*, and at its *20* lower end it is held in place by means of a pin *n*, which is secured within a slot *o* in a bracket *p*, attached to the under side of the table. (See Fig. 4.) The pin *n* is clamped in position within the slot *o* by means of the *25* screw-nut *q*. The detail view Fig. 4^a shows the pin and the method of its attachment to the bracket *p* clearly. In this view *n'* is a square made on the lower end of the pin, so as to prevent its movement within the slot *o*.

30 *r* is a block attached to the side of the board *l* for the purpose of depressing it easily. As will be seen, the end *l³* of the board *l* is slightly curved at its upper side and, as will also be seen, the table is recessed at *a'*, and the side *a²* *35* of the recess is curved and faced with brass or other metal.

s is a plate fitted on the table *a* and having an upturned edge *s'*. The bag-bottoms after being pasted are pressed and flattened on this *40* plate *s*.

t is a receptacle for the bags to be pasted.

If desired, a paster with its accessories can be fitted at each end of the table *a*.

The arrow *u* at Fig. 3 indicates the direction in which the bags, after being pasted, are inserted in the presser *l*, and the arrow *u'* indicates the direction taken by the bags as they tumble over the inclined end *l³* of the presser-board.

v is the body of a paper bag. *w* is the bottom of said bag. *x* are triangular flaps forming part of the bottom when turned in and pasted down, as in Fig. 8.

Having now fully described my invention, what I claim, and desire to secure by Letters Patent, is—

1. In pasting mechanism, a table, a paste vessel secured to the table and a pasting-tongue with a roof-like top and working in the bottom of the paste vessel. *60*

2. In pasting mechanism, a table, a paste vessel secured to the table, a tongue with a roof-like top fitted in the bottom of the paste vessel, a link secured to the tongue, a lever for operating the link and means for operating the lever, substantially as set forth. *65*

3. In pasting mechanism, a table, a paste vessel secured to the table, a tongue fitted in the bottom of the paste vessel, a link secured to the tongue, a lever for operating the link, *70* a spring connected to the lever and treadle mechanism for depressing the lever, substantially as set forth.

4. In pasting mechanism, a table, a paste vessel secured to the table, a paste-regulating gate in the paste vessel, a tongue fitted in the bottom of the paste vessel and means for reciprocating the tongue, toward or from said gate, substantially as set forth. *75*

5. In pasting mechanism, a table, a paste vessel secured thereto, a reciprocatory tongue with a roof-like top in the bottom of the paste vessel, means for moving the tongue, and a regulating-gate movable toward and from said tongue. *80*

6. In pasting mechanism, a pressing device consisting of plate *l* having rounded end *l³* and hinged to the lower side of the table-top, a spring intended to raise said plate there being an opening in the table top, and having a rounded edge *a²*, as set forth. *85*

Signed at Glasgow, Scotland, this 13th day of December, A. D. 1897.

WILLIAM CARTER.
